UNITED STATES PATENT OFFICE.

ALFRED FORNANDER, OF NEW YORK, N. Y., ASSIGNOR TO DAIRY OILS EXTRACTING COMPANY, OF NEW YORK, N. Y., A CORPORATION OF NEW YORK.

APPARATUS FOR TREATING MILK AND OTHER LIQUIDS.

1,013,595.

Specification of Letters Patent.

Patented Jan. 2, 1912.

Application filed March 10, 1910. Serial No. 548,446.

To all whom it may concern:

Be it known that I, ALFRED FORNANDER, a citizen of the United States, and a resident of the borough of Manhattan of the city of New York, in the State of New York, have invented certain new and useful Improvements in Apparatus for Treating Milk and other Liquids, of which the following is a specification, reference being had to the accompanying drawings, forming a part hereof.

The invention relates more particularly to improvements in machines of the type shown and described in United States Letters Patent No. 917,008, dated April 6, 1909, in which type of machines the liquid to be treated is delivered into a very narrow space between two disks having opposed roughened faces and rotating with considerable

20 relative movement in respect to each other.

The main object of the invention is to provide an apparatus of this sort in which there will be no tendency of the disks to vary their distance with respect to each other, whereby 25 the treatment of the liquid may remain uniform and the proper and smooth running of the machine continue unaffected. For, I have discovered that in some machines having the rotating disks, a partial vacuum is 30 produced between the disks by the centrifugal action, which tends to draw the disks together; and that this not only interferes with the smooth running of the machines, but the variation of the distance between the 35 faces of the disks produces considerable difference in the treatment effected by the machines.

One embodiment of the invention by means of which the foregoing objections 40 may be overcome is shown in the accompanying drawings in which,

Figure 1 is a view thereof in elevation. Fig. 2 is a view in central vertical section, with the funnel and motor omitted, and, 45 Figs. 3 and 4 are plan views of the rotating member as seen respectively from the irregular planes indicated by the lines 3-3 and 4-4 in Fig. 2.

In the case of the present embodiment, 50 there are two sets of disks with opposed roughened faces, as the rotating member *a* presents a roughened face to each side-member *b* of its inclosing casing (Fig. 2). This rotating member has a shaft *c* fastened 55 therein by a set screw *d* and is driven by a

motor *x* which, as shown, is connected directly thereto. The milk or other liquid to be treated is introduced through a funnel *e* and is delivered into a hollow shaft *f*, forming one of the journals of the rotating member, whence it finds its way into the interior of the rotating member. The latter is formed with radial ducts *g* through which the liquid is caused to flow by centrifugal action until it reaches the periphery of the 60 rotating member, whence it is driven, by the liquid behind it, around the edges of said member and back across both faces and between the faces and the flanges *b* of the casting. These flanges or side-members *b* are 65 ring-shaped, being secured together, face to face, by bolts *h* and, as a single piece, are fastened to a support *i* by a bracket *k*. A packing ring *m*, moreover, is preferably provided between the abutting surfaces of these 70 members. The inner opposing faces thereof are provided with a large number of small recesses *n* with sharp edges similar to those indicated at *o* on the faces of the rotating member *a* to provide the desired roughening. The milk or other liquid will, therefore, be pushed across the space between these roughenings upon either side of the 75 rotating member and will be discharged from near the center of the rotating member. A shell *p* surrounds this portion of the mechanism and the treated liquid will be delivered from an opening or spout at the lower end of said shell.

It will be seen that with the present improvements, there can be no tendency of the centrifugal action to produce a vacuum between the opposed roughened surfaces and that, hence, there will be no tendency for these faces to draw together. Moreover, as 90 the pressures on both sides of the rotating member *a* are the same, the latter will be perfectly balanced and will always maintain its true position so that a uniform distance between the roughened surfaces, and therefore a uniform action, is always assured.

Besides using the present improvements for emulsifying milk to extract the butter fat therefrom, it may also be used to effect the sterilization of milk and other liquids 105 without destroying any of the nutritive qualities of the milk or without otherwise detrimentally affecting the same, which, obviously, cannot be done by heating or the usual process of pasteurization.

Various changes may be made in the present embodiment of the improvements without departing from the spirit of the invention.

5 I claim as my invention:

1. In an apparatus for treating milk and other liquids, the combination of a rotating member, and a casing therefor arranged to form a narrow space with the rotating member on each side thereof, said casing having an opening through its central portion adjacent to the rotating member to provide an exit for the treated substance.
2. In an apparatus for treating milk and other liquids, the combination of a rotating member formed to permit liquid to pass through it from center to periphery, a casing therefor arranged to form a narrow space with the rotating member on each side thereof, means to supply milk between the outer portion of the space between the member and casing and to cause the milk to pass inwardly between said member and casing and means to permit the treated substance to pass from the central portion of the space between said member and casing.
3. In an apparatus for treating milk and other liquids, the combination of a rotating member, a casing therefor arranged to form a narrow space with the rotating member on each side thereof, the adjacent faces of the rotating member and casing being roughened and means to permit the treated substance to pass from the central portion of the space between the members.
4. In an apparatus for treating milk and other liquids, the combination of a member formed to permit liquid to pass through it from center to periphery, and a casing therefor arranged to form a narrow space with the rotating member on each side thereof, said casing inclosing the periphery of the member, the adjacent faces of the member and casing being roughened and the member and casing having relative rotary movement therebetween.
5. In an apparatus for treating milk and other liquids the combination of a rotating member, a casing therefor containing two rings forming a narrow space with the rotating member on each side thereof and leaving the center of said member exposed.
6. In an apparatus for treating milk and other liquids, the combination of a rotating

member formed to permit liquid to pass through it from the center to the periphery, a casing therefor containing two rings forming a narrow space with the rotating member on each side thereof and leaving the center of said member exposed.

7. In an apparatus for treating milk and other liquids, the combination of a rotating member, a casing therefor containing two rings forming a narrow space with the rotating member on each side thereof and leaving the center of said member exposed, the adjacent faces of the rotating member and rings being roughened.

8. In an apparatus for treating milk and other liquids, the combination of a rotating member formed to permit liquid to pass through it from the center to the periphery, a casing therefor containing two rings forming a narrow space with the rotating member on each side thereof and leaving the center of said member exposed, the adjacent faces of the rotating member and rings being roughened.

9. In an apparatus for treating milk and other liquids, the combination of a rotating member formed to permit liquid to pass through it from center to periphery, a stationary casing therefor arranged to form a narrow space with the rotating member on each side thereof, and a hollow shaft to deliver liquid to the center of the rotating member.

10. In an apparatus for treating milk the combination of coöperating members one of which revolves relative to its companion member, means for supplying milk between the members at the outer portion thereof and means for withdrawing the treated substance through the central portion of one of the members.

11. In an apparatus for treating milk coöperating disks or members relatively rotatable and means for forcing milk inwardly between the members and for forcing the treated substance from between the members at the central portion thereof.

This specification signed and witnessed this 31st day of January, A. D., 1910.

ALFRED FORNANDER.
